(57) **CLAIM**

The ornamental design for an electronic pillar candle, as shown and described.

DESCRIPTION

FIG. 1 is an isometric view of the electronic pillar candle; FIG. 2 is a front view of the electronic pillar candle of FIG. 1; FIG. 3 is a rear view of the electronic pillar candle of FIG. 1; FIG. 4 is a left side view of the electronic pillar candle of FIG. 1;

FIG. 5 is a right side view of the electronic pillar candle of FIG. 1;

FIG. 6 is a top view of the electronic pillar candle of FIG. 1; and,

FIG. 7 is a bottom view of the electronic pillar candle of FIG. 1.

The broken-line disclosure represents portions of the electronic pillar candle which form no part of the claimed design.
